UNITED STATES PATENT OFFICE

134,141

DESIGN FOR A WHISK BROOM

Ellis L. Smith, Freeport, Ill.

Application June 15, 1942, Serial No. 107,213

Term of patent 7 years

To all whom it may concern:

Be it known that I, Ellis L. Smith, a citizen of the United States, residing at Freeport, in the county of Stephenson and State of Illinois, have invented a new, original, and ornamental Design for a Whisk Broom, of which the following is a specification, reference being had to the accompanying drawing, forming part thereof.

In the drawing:

Fig. 1 is a perspective view of a whisk broom showing my new design.

Fig. 2 is an elevational view thereof.

Fig. 3 is a top plan view thereof.

I claim:

The ornamental design for a whisk broom, as shown.

ELLIS L. SMITH.
